PIANO ACTION

Charles Frederick Stein, Ivoryton, Conn., assignor
to Pratt, Read and Company, Inc., Ivoryton,
Conn., a corporation of Connecticut

Application April 9, 1945, Serial No. 587,372

16 Claims. (Cl. 84—240)

1

This invention relates to piano actions and, while it is of general application, it is particularly suitable for embodiment in pianos of the low-upright type.

The increasing popularity of the low-upright and spinet models of pianos in recent years has raised the problem of devising a satisfactory piano action. In the old style high-upright pianos, it was customary to interconnect the capstan on the end of each key to its associated hammer butt through a strut linkage including a fly-jack for releasing the hammer at the end of the stroke. This piano action was of such construction that it had to be mounted entirely above the level of the keys, so that a corresponding vertical height in the piano frame and case was required. In the low-upright style of piano there is insufficient vertical space relative to the level of the keys to accommodate this type of action.

Certain piano actions have been devised for the new low-upright pianos having a so-called drop-action, that is, a mechanism comprising a number of links dropping below and behind the piano keybed. Such mechanisms have in some instances introduced undesirable frictional dissipation of the striking force initiated by the key and a certain sluggishness in the return of the striking hammer to its rest position, resulting in a "slow" piano action, and in general have been clumsy to handle. Also in any piano actions there are a number of elements which must be made adjustable, both for proper setting of the striking hammer in the first instance and to compensate for subsequent wear, shrinkage of wooden parts, etc. In the drop-type action, these adjustable elements are generally below and behind the piano keybed and quite inaccessible for adjustment without at least a partial disassembly of the piano.

It is an object of the invention, therefore, to provide a new and improved piano action which is of general application but which is particularly suitable for embodiment in low-upright pianos, and one which will obviate one or more of the shortcomings and limitations of the prior art piano actions of this type.

It is another object of the invention to provide a new and improved piano action which is extremely simple and rugged in construction, and reliable and fast in operation.

It is still another object of the invention to provide a new and improved piano action which is particularly suitable for installation in a low-upright type of piano, and in which all of the adjustable elements are accessible for ready adjustment from above and in front of the keys.

2

In accordance with the invention, an action for a piano including a plurality of keys comprises a pivoted striking hammer, a single pivoted, normally rigid, collapsible actuating mechanism disposed to be operated by a key and engaging the hammer for actuating the same, and means for collapsing the mechanism at a predetermined point of the travel of the hammer to permit the hammer to fall back from string-striking position prior to the release of its associated key. In a preferred form of the invention, the collapsible actuating mechanism comprises a rigid three-hinged actuating frame member including a substantially horizontal first arm disposed to be operated by a key and a second arm engaging the second hammer for actuating the same. One of the arms has an abutment thereon and there is provided a third arm hinged to the other of the arms and normally engaging the abutment. In this arrangement the means for collapsing the mechanism comprises means for disengaging the third arm from the abutment and may be in the form of an adjustable stop in the path of movement of the third arm.

For a better understanding of the invention, together with other and further objects thereof, reference is had to the following description taken in connection with the accompanying drawings while its scope will be pointed out in the appended claims.

Referring now to the drawings, Fig. 1 is an end view of an action for a single piano key in the position of rest; Fig. 2 is a view of the action of Fig. 1 showing the hammer in the approximate string-striking position; while Figs. 3 and 4 are end views of a modified form of piano action at rest and in action, respectively.

Referring now to Fig. 1 of the drawings, there is illustrated an action for a piano having a plurality of keys comprising a striking hammer 10 having a contact butt 10a. The hammer 10 is adapted to strike a string 9 and to be actuated by a piano key 11 pivotally mounted from a key frame 12, its actuating end resting on a back-rail cloth 13.

The piano action comprises a single pivoted, normally rigid, collapsible actuating mechanism disposed to be operated by the key 11 and engaging the hammer butt 10a for actuating the same. This collapsible actuating mechanism is in the form of a rigid three-part hinged actuating frame including a substantially horizontal first arm 14 extending above its associated key 11 and disposed to be operated by a capstan 15 mounted at the outer end of the key 11. The arm 14

is pivoted at 14a to a flange 15 depending from and secured to a rail 16. The three-part frame also includes a second arm or actuator 17 pivoted to the arm 14 near its free end at the point 17a and depending from the arm 14. The actuator 17 has a contact surface 17b engaging the hammer 10 for actuating the same, specifically engaging the end surface on the hammer butt 10a. One of the arms 14 and 17, specifically the arm 14, has an abutment 14b thereon near its free end and beyond the pivot point 17a, and the frame includes also a third arm or fly-jack 18 pivoted or hinged at 18a to an extension 17c of the arm 17 beyond its pivot point 17a and normally engaging the abutment 14b. The actuating frame also includes biasing means such as a helical compression spring 19 for normally maintaining the arm 18 in engagement with the abutment 14b and retaining the collapsible actuating mechanism in the form of a rigid frame.

The piano action of the invention also includes adjustable means for collapsing the actuating mechanism at a predetermined adjustable point in the travel of the hammer 10 to permit the hammer to fall back from a string-striking position prior to the release of its associated key 11. Such collapsing means comprises means for breaking one of the hinges of the hinged actuating frame, specifically, a stop 20 adjustably supported in a rail 21 and in the path of movement of an extension of the arm 18 beyond its pivot point 18a during the movement of the actuating mechanism into striking position. This engagement is shown in Fig. 2 which will be referred to in more detail in connection with the operation of the piano action. Engagement of the arm 18 with the stop 20 is effective to disengage the arm from the abutment 14b to collapse the frame.

The piano action of the invention also includes adjustable means for limiting the extent of the collapse of the actuating frame or mechanism to support the hammer near string-striking position so long as the key is depressed. This means is in the form of an adjustable stop 22 on one of the arms of the frame, for example the horizontal arm 14, engaging a butt 17f on the arm 17 upon collapse of the frame, thereby to limit the extent of collapse thereof. The stops 20 and 22 are provided with threaded adjusting eyes or heads 20a, 22a, respectively, and these are both accessible for adjustment from above the piano key 11 and at the front of the piano action as a whole.

The hammer butt 10a is pivotally supported at 10c from a flange 23 secured to a lower action rail 24. The hammer 10 is biased into its position of rest by means of a spring 26 mounted on a spring rail 27. Associated with the action described is a damper 28 supported by a damper wire 29 from a damper lever 30 pivotally mounted at 30a from a flange 31 secured to the lower action rail 24. The arm 17 is provided with an extending rod 17d engaging the felt 30b secured to the lower end of the damper lever 30. The lower portion of the damper lever 30 is also provided with a damper felt 30c adapted to be engaged by a damper-lifting rod 32. A hammer rest rail 33 is provided for supporting the hammer 10 in its position of rest.

It is believed that the operation of the piano action of the invention will be apparent from the foregoing description. In brief, however, assuming that the mechanism is in the position of rest as shown in Fig. 1, depression of the key 11

is effective to rotate the collapsible actuating frame 14-17-18 in a clockwise direction about its pivot 14a, the spring 19 retaining the arm 18 in engagement with the abutment 14b and thus retaining the mechanism in the form of a rigid three-hinged frame. The frame 14-17-18 is thus actuated as a unit, its actuating face 17b contacting the butt 10a of the hammer 10 and rotating it in a counterclockwise direction into string-striking position. Prior to reaching the string-striking position of the hammer 10, the head portion of the rod 17d engages the operating arm 30b of the damper lever 30 to lift the damper from the string in order to produce a sustained note so long as the key is depressed.

At about the time that the hammer 10 reaches its string-striking position, the extension of the arm 18 beyond the pivot point 18a engages the adjustable stop 20, which disengages the arm 18 from the abutment 14b and is effective to collapse the frame member 14-17-18, permitting the arm 17 to rotate about its pivot 17a in a counterclockwise direction until the butt of the arm engages the adjustable stop 22. This permits the hammer 10 to fall back, rotating in a clockwise direction about its pivot point 10c, the hammer butt 10a maintaining its engagement with the contact face 17b of the arm 17. This final position, after the striking of a note, is maintained so long as the key 11 is depressed. This final position is illustrated in Fig. 2 of the drawings.

Upon release of the key 11, the weight of the hammer 10 and of the actuating mechanism 14-17-18 causes it to fall back rapidly. During this return to rest position, the extension of the arm 18 is released from the stop 20 and the compression spring 19 snaps it back quickly into engagement with the arm 14 at the abutment 14b so that, upon a subsequent striking of the key 11, it is in position immediately to repeat the action described above. The force of the spring 19 is so adjusted in relation to the weights and inertias of the several parts of the piano action that the arm or fly-jack 18 is restored to its rest position during the return movement of the action mechanism as a whole, preferably some distance prior to reaching the rest position of the key and piano action mechanism. This ensures that the mechanism is ready for a repeated stroke of the key 11 in the very minimum of time and thus contributes to an extremely fast piano action. In fact a pianist is able to feel in his fingers when the action is in position to again move the hammer and with the present mechanism, in view of the fact that the parts are in position for striking another blow with the hammer before the key is in final rest position the "repetition" blow can be started in less time than it requires the parts and key to reach a final position of rest.

On the other hand, as mentioned above, the butt of the arm 17 is maintained in engagement with the stop 22 so long as the key 11 is depressed so that, in turn, the contact face 17b is maintained in engagement with the hammer butt 10a. Therefore, if for any reason the arm 18 should lag in its return to its normal position, the stop 22 provides an auxiliary rigid connection between the arm 14 and the arm 17 so that a repetitive blow on the key 11 is effective to cause the hammer 10 to strike the string 9. Furthermore, at any intermediate position after the key 11 has been released and before it reaches the final rest position, the engagement of the butt

of arm 17 by the stop 22 maintains a rigid connection between the key 11 and the hammer butt 10a to permit repetitive blows from such intermediate position. This condition continues until the action mechanism returns nearly to its position of rest, as illustrated in Fig. 1, in which position the stop 22 is disengaged from the arm 17. In other words there is no lost motion between the key 11 and the hammer 10 from the time that the hammer is first struck until the action mechanism returns nearly to its position of final rest as represented in Fig. 1. It will be understood also that the stop 22 acts in a conventional manner to determine the position to which the hammer 10 returns when the key is maintained depressed.

It is noted that the piano action described overcomes the several disadvantages and limitations of the prior art piano actions for low-upright pianos described above. That is, the adjustable capstan 15 and the adjustable eyes 20a and 22a of the stops 20 and 22, respectively, are all above the keybed and in front of the major components of the piano action so that they are readily accessible from the front of the piano. At the same time, the hammer 10 is only slightly above the keybed, thus permitting the installation of the piano action in a very low-upright piano. Also the piano action as a whole extends only a few inches, for example about two inches, below the keybed so that all parts thereof are reasonably accessible for repair, replacement or adjustment without disassembly of the piano as a whole. At the same time, the actuating mechanism is, during the striking operation, in the form of a simple, rigid, three-hinged frame 14-17-18 including only a single pivotal connection at 14a, thus largely eliminating the dissipation of the key-striking force by friction, which results from the use of the complicated action of the prior art involving a large number of relatively pivoted elements. However, the collapse of the actuating mechanism upon reaching the string-striking position is effective to permit the immediate rebound of the hammer 10 and an extremely rapid return of the elements to rest position upon release of the piano key 11 for a very rapid repetitious movement of the entire mechanism.

The modified form of action illustrated in Figs. 3 and 4 is generally similar to that of Figs. 1 and 2 and such elements as they correspond to those of Figs. 1 and 2 are identified by the same reference numerals. The essential difference of the piano action of Figs. 3 and 4 is that the disengageable arm 38 of this modified form is pivoted at 38a from the main portion of the horizontal arm 34 and engages an abutment 37c formed in the main portion of the depending arm or actuator 37 which is pivoted at 37a near the free end of the horizontal arm 34, which is substantially the inverse of the arrangement of Figs. 1 and 2. In this instance, the spring 39 is a tension spring rather than a compression spring and biases the arms 34 and 37 toward collapse which is opposed by the arm 38. As in the arrangement of Figs. 1 and 2, the arm 37 is provided with a contact surface 37b for engaging the hammer butt 10a to actuate the same and with an extension rod 37d terminating in a head 37e for actuating the damper lever 30. The arm 34 is provided with a projection 34b which cooperates with an adjustable stop 22a supported in an extension 37f of the arm 37 to limit the extent of collapse of the actuating mechanism.

34-37-38 upon disengagement of the arm 38 from the abutment 37c. The arm 38 is provided with an extension 38b which is engaged by the adjustable stop 20 in its path of movement toward the string-striking position of the hammer 10.

The general principle of operation of the modified form of invention illustrated in Figs. 3 and 4 is entirely similar to that described above and need not be repeated. The position of the several parts in string-striking position of the hammer 10 is shown in Fig. 4, the dotted-line position of the hammer 10 representing its striking position and the solid-line position, the position to which the hammer falls back while the key 11 is maintained depressed. The piano action of Figs. 3 and 4 has generally the advantageous characteristics described above in connection with that of Figs. 1 and 2. The choice as between the two forms of the invention is determined primarily by the nature of the installation and the convenience in mechanically accommodating the different arrangement of the parts of the collapsible actuating mechanism.

While there have been described what are at present considered to be the preferred embodiments of the invention, it will be apparent to those skilled in the art that various changes and modifications may be made therein without departing from the spirit or scope of the invention.

What is claimed as new is:

1. An action for a piano including a plurality of keys comprising, a pivoted striking hammer, a single pivoted normally rigid collapsible actuating mechanism disposed to be operated by a key and including a portion engaging said hammer for actuating the same, said hammer being free to move with respect to said portion of said mechanism, and means for collapsing said mechanism at a predetermined point in the travel of said hammer to permit said hammer to fall back from string-striking position prior to release of its associated key.
2. An action for a piano including a plurality of keys comprising, a pivoted striking hammer, a single pivoted rigid actuating frame disposed to be engaged by a key and engaging said hammer for actuating the same, said hammer being free to move independently of said mechanism, said actuating frame including a plurality of members hinged together and adapted to be normally held in fixed position with respect to each other, and means for breaking a hinge of said actuating frame to collapse the same at a predetermined point in the travel of said hammer, thereby to permit said hammer to fall back from string-striking position prior to release of its associated key.
3. An action for a piano including a plurality of keys comprising, a pivoted striking hammer, a single pivoted normally rigid collapsible actuating mechanism including a substantially horizontal arm disposed to be engaged by a key and a depending arm engaging said hammer for actuating the same, and means for collapsing said mechanism at a predetermined point in the travel of said hammer to permit said hammer to fall back from string-striking position prior to release of its associated key.
4. An action for a piano including a plurality of keys comprising, a pivoted striking hammer, a single pivoted normally rigid collapsible actuating mechanism including a fly-jack as an element thereof and disposed to be operated by a

key and engaging said hammer for actuating the same, said hammer being free to move independently of said mechanism, and means for actuating said fly-jack to collapse said mechanism at a predetermined point in the travel of said hammer, thereby to permit said hammer to fall back from the string-striking position prior to release of its associated key.

5. An action for a piano including a plurality of keys comprising, a pivoted striking hammer having a contact butt, a single pivoted normally rigid collapsible actuating mechanism disposed to be operated by a key and including a portion adapted to contact said hammer butt for actuating the same, said hammer being free to move with respect to said portion of said mechanism, and means for collapsing said mechanism at a predetermined point in the travel of said hammer to permit said hammer to fall back from string-striking position prior to release of its associated key.

6. An action for a piano including a plurality of keys comprising a pivoted striking hammer, a single pivoted collapsible actuating mechanism disposed to be operated by a key and engaging said hammer for actuating the same, said hammer being free to move with respect to said mechanism, biasing means for normally retaining said mechanism in the form of a rigid actuating frame member, and means for collapsing said mechanism at a predetermined point in the travel of said hammer to permit said hammer to fall back from string-striking position prior to release of its associated key.

7. An action for a piano including a plurality of keys comprising, a pivoted striking hammer, a single pivoted rigid hinged actuating frame including a substantially horizontal arm disposed to be engaged by a key and a depending arm engaging said hammer for actuating the same, and means for breaking a hinge of said actuating member to collapse the same at a predetermined point in the travel of said hammer to permit said hammer to fall back from string-striking position prior to release of its associated key.

8. An action for a piano including a plurality of keys comprising, a pivoted striking hammer, a single normally rigid collapsible actuating mechanism including a substantially horizontal first arm extending above its associated key to be operated thereby and pivoted at one end and a second arm depending from said first arm near its free end and engaging said hammer for actuating the same, and means for collapsing said mechanism at a predetermined point in the travel of said hammer to permit said hammer to fall back from string-striking position prior to release of its associated key.

9. An action for a piano including a plurality of keys comprising, a pivoted striking hammer, a single pivoted rigid three-part hinged actuating frame including a substantially horizontal first arm disposed to be operated by a key, a second arm engaging said hammer for actuating the same, one of said arms having an abutment thereon, and a third arm hinged to the other of said first two mentioned arms and normally engaging said abutment, and means for disengaging said third arm from said abutment to collapse said frame at a predetermined point in the travel of said hammer, thereby to permit said hammer to fall back from string-striking position prior to release of its associated key.

10. An action for a piano including a plurality of keys comprising, a pivoted striking hammer,

7

a single pivoted rigid three-part hinged actuating frame including a substantially horizontal first arm disposed to be operated by a key, a second arm engaging said hammer for actuating the same, said first arm having an abutment thereon, and a third arm hinged to said second arm and normally engaging said abutment, and means for disengaging said third arm from said abutment to collapse said frame at a predetermined point in the travel of said hammer, thereby to permit said hammer to fall back from string-striking position prior to release of its associated key.

11. An action for a piano including a plurality of keys comprising, a pivoted striking hammer, a single pivoted rigid hinged actuating frame including a substantially horizontal first arm disposed to be operated by a key, a second arm engaging said hammer for actuating the same, said second arm having an abutment thereon, and a third arm hinged to said first arm and normally engaging said abutment, and means for disengaging said third arm from said abutment to collapse said frame at a predetermined point in the travel of said hammer, thereby to permit said hammer to fall back from string-striking position prior to release of its associated key.

12. An action for a piano including a plurality of keys comprising, a pivoted striking hammer, a single pivoted normally rigid collapsible actuating mechanism including a fly-jack as an element thereof and disposed to be operated by a key and engaging said hammer for actuating the same, said hammer being free to move independently of said mechanism, and a stop in the path of movement of said fly-jack for actuating the same to collapse said mechanism at a predetermined point in the travel of said hammer, thereby to permit said hammer to fall back from string-striking position prior to release of its associated key.

13. An action for a piano including a plurality of keys comprising, a pivoted striking hammer, a single pivoted normally rigid collapsible actuating mechanism disposed to be operated by a key and engaging said hammer for actuating the same, said hammer being free to move independently of said mechanism, means for collapsing said mechanism at a predetermined point in the travel of said hammer to permit said hammer to fall back from string-striking position prior to release of its associated key, and means for limiting the extent of collapse of said mechanism to support said hammer near string-striking position.

14. An action for a piano including a plurality of keys comprising, a pivoted striking hammer, a single pivoted rigid hinged actuating frame including a substantially horizontal first arm disposed to be operated by a key, a second arm engaging said hammer for actuating the same, one of said arms having an abutment thereon, and a third arm hinged to the other of said first two mentioned arms and normally engaging said abutment, and means for disengaging said third arm from said abutment to collapse said frame at a predetermined point in the travel of said hammer, thereby to permit said hammer to fall back from string-striking position prior to release of its associated key, and a stop on one of said first and second arms for engaging the other upon collapse of said frame to limit the extent of collapse thereof, thereby to support said hammer near string-striking position.

15. An action for a piano including a plurality of keys comprising, a pivoted striking hammer,

a single pivoted rigid hinged actuating frame including a substantially horizontal first arm disposed to be operated by a key, a second arm engaging said hammer for actuating the same, one of said arms having an abutment thereon, and a third arm hinged to the other of said first two mentioned arms and normally engaging said abutment, an adjustable stop in the path of movement of said third arm for disengaging the same to collapse said frame at a predetermined point in the travel of said hammer, thereby to permit said hammer to fall back from string-striking position prior to release of its associated key, and an adjustable stop on one of said first and second arms for engaging the other upon collapse of said frame to limit the extent of collapse thereof, thereby to support said hammer near string-striking position.

16. An action for a piano including a plurality of keys comprising, a pivoted striking hammer, a single pivoted normally rigid collapsible actuating mechanism disposed to be operated by a key and engaging said hammer for actuating the same, adjustable means for collapsing said mechanism at a predetermined adjustable point

10
in the travel of said hammer to permit said hammer to fall back from string-striking position prior to release of its associated key, and adjustable means for limiting the extent of collapse of said mechanism to support said hammer near string-striking position, both of said adjustable means being accessible for adjustment above the piano keys.
